UNITED STATES PATENT OFFICE

JAMES L. HATCHER, OF THE UNITED STATES ARMY, WINCHESTER, VIRGINIA

MUZZLE ATTACHMENT FOR GUNS

Application filed June 6, 1927. Serial No. 196,951.

(GRANTED UNDER THE ACT OF MARCH 3, 1883, AS AMENDED APRIL 30, 1928; 370 O. G. 757)

The invention described herein may be manufactured and used by or for the Government for governmental purposes without the payment to me of any royalty thereon.

5 This invention relates to a muzzle attachment for guns and more specifically it has reference to that class of attachments serving separately or severally to conceal flash, check recoil, silence the report and arrest the tendency of the gun to climb.

10 The essential features which distinguish the present attachment from those heretofore designed reside in the provisions for controlling and directing the admission of the gases into the dampening passage, confining them to the passage, and directing their discharge in a manner to utilize their energy in arresting the climb of the gun.

15 With the foregoing and other objects in view, my invention resides in the novel arrangement and combination of parts and in the details of construction hereinafter described and claimed, it being understood that changes in the precise embodiment of the invention herein disclosed may be made within 20 in the scope of what is claimed without departing from the spirit of the invention.

25 Fig. 1 is a longitudinal sectional view of the attachment mounted on the muzzle of a gun;

30 Fig. 2 is a sectional view on the line 2—2 of Fig. 1.

Fig. 3 is a view in front elevation of the assembly;

35 Fig. 4 is a fragmentary longitudinal sectional view of a modified form of the attachment;

Fig. 5 is a front end view of Fig. 4;

40 Fig. 6 is a detailed view of the bullet tube having the impact plate directly mounted thereon.

Referring to the drawings by numerals of reference:

The attachment comprises a tubular casing 45 5 interiorly threaded at the rear end 6 for securing it to the muzzle of a gun. Fixed in the casing is an impact and shearing plate 7 which is spaced from the rear end of the casing to provide an expansion chamber 8.

50 The plate 7 is in the form of a disk having

marginal openings 9 whose combined area is at least and preferably equal to the area of the bullet passage in the rearwardly disposed tubular extension 10.

Disposed forwardly of the impact plate is 55 a helical baffle 11 which may embrace an axial tube 12 and having its outer edges suitably secured to the casing as in grooves 13 in the inner wall thereof. If desired, the tube 12 may be integral with the tubular extension 10 of the impact plate as shown in Fig. 6. 60 The forward extremity of the baffle is terminated at or below the horizontal plane of the axis of bore so that the discharging gases may be made to impinge on a projecting deflection plate 14 provided for the purpose of 65 increasing the area of the reaction surface and obtaining a downward thrust which will compensate for the tendency of the gun to climb.

70 The device will function according to the same principle even with the deflection plate removed from the cap ring 15 but under such circumstances the forward extremity of the casing is modified as shown in Fig. 4 so that 75 the assembly may be turned 180° whereby the discharge of the gases is directed upwardly as indicated in Fig. 5. In this case the area of reaction $x-y$ will exceed the discharge area ab .

80 As the projectile emerges from the gun and occupies the axial passage 10 of the impact plate the gases will be blocked off and will be obliged to pass through the marginal openings 9 towards which they are directed by 85 reason of the shape of the impact plate. The entrance of the gases into the dampening passage of the baffle is directed adjacent the wall of the casing and is of special significance in initiating circulation when the axial tube 12 90 is not incorporated in the assembly. The axial tube 12 will secure the circuitous flow of the gases and will confine them to the dampening passage.

I claim:

95 1. An attachment for guns embodying a casing, an impact plate spaced from the rear of the casing to provide an expansion chamber and formed with a rearwardly extending projectile passage, said plate having marginal 100

openings whose combined area equals the area of the opening of the projectile passage, an axial imperforate tube in the casing forwardly of the impact plate and a helical baffle embracing the tube and terminating to provide a discharge area less than the reaction area of the casing.

5 2. An attachment for guns embodying a casing, an impact plate spaced from the rear 10 of the casing to provide an expansion chamber and formed with a rearwardly extending projectile passage, said plate having marginal openings whose combined area equals the area of the opening of the projectile passage, an 15 axial imperforate tube in the casing forwardly of the impact plate, and a helical baffle embracing the tube.

20 3. An attachment for guns embodying a casing, an axial imperforate tube in the casing spaced from its rear end, an impact plate embracing the tube forwardly of its rear extremity and having marginal openings whose combined area equals the area of the opening in the tube and a helical baffle embracing 25 the tube forwardly of the impact plate.

25 4. An attachment for guns embodying a casing, an axial imperforate tube in the casing spaced from its rear end, an impact plate embracing the tube forwardly of its rear extremity and having marginal openings and a helical baffle embracing the tube forwardly 30 of the impact plate.

JAMES L. HATCHER.
